POSITIVE DISPLACEMENT PUMP

Harold Becher, Brooklyn, and Cleburne B. Hatfield, New York, N.Y., assignors to Strato-Missiles, Inc., New York, N.Y.

Filed Mar. 8, 1962, Ser. No. 178,392

2 Claims. (Cl. 230—149)

This invention relates to pumps, more particularly to pumps of the compressor type, having positive displacement characteristics.

This application is a continuation in part of the copending application of Cleburne B. Hatfield, Serial No. 494,634, filed March 16, 1955, issued as United States Patent No. 3,024,596, for a Propulsion System.

One object of this invention is to provide a compressor capable of compressing gases to very high pressures at high operating efficiencies.

Another object of our invention is to provide a positive displacement pump having a large volumetric displacement capacity.

Another object is to provide a compressor which is light in weight, compact in structure and easy to manufacture.

Another object is to provide a compressor having simultaneously rotary as well as reciprocating action.

Another object is to provide a pump capable of transferring simultaneously two or three separate and distinct fluids.

Other objects will appear more fully upon consideration of the detailed description of the embodiment of the invention which follows herein. Although one specific form of the compressor is described and illustrated in the following drawings, it is to be understood that the drawings are for the purpose of illustration only and shall not be construed as defining the scope of the invention for which latter purpose reference should be had to the appended claims.

Referring to the drawings:

FIGURE 1 is a vertical longitudinal section view of the pump.

FIGURE 2 is a transverse section view of FIGURE 1 along A—A.

FIGURE 3 is a transverse section view of FIGURE 1 along B—B.

FIGURE 4 is a transverse end view of FIGURE 1 along C—C.

FIGURE 5 is a transverse section view of FIGURE 1 along D—D.

FIGURE 6 is a section view of FIGURE 2 along E—E, in FIGURE 2.

FIGURE 7 is a view of FIGURE 2 along G—G.

FIGURE 8 is a view of a fragment of FIGURE 1 along F—F.

Referring to FIGURES 1 and 2, a shaft 1 is shown supported on each end by a sleeve bearing 2. These sleeve bearings are supported by the projecting portions 3 of the end housing 4. The shaft 1 has splines 5 formed as an integral part of the shaft, during a major portion of its length, and which fit into internal splines 6 of the rotor 7. This compels the rotor to rotate in unison with the shaft. An annular housing 8, substantially cylindrical in overall shape encloses the outer perimeter of the pump unit and has protruding portions 9 containing slots 10 adapted to receive radially reciprocating gates 11. The slots 10 are rectangular spaces enclosed at the top by the portion 12 of the protrusion 9, and are equal in height to the housing 8.

The radially reciprocating gate 11 is provided with rollers or needle bearings 15, one near each end 14 of the gate 11, or a total of 4 rollers. Bearing pins 16 are inserted through the needle bearings, as shown. The holes 17 are formed through the ends 14 of gate 11 to permit

2

the insertion of the bearing pin 16 and the assembly of the rollers 15 in place. The four rollers 15 roll on the surface of the rotor 7, which is formed of three lobes, 7a, 7b and 7c, each located at one third of a circle or 120 degrees apart. The surface of the rotor and three lobes are formed with a curve of such configuration that as the cylindrical surface of the upper and lower rollers 15 roll upon the surface of the rotor 7, they will at all times contact or bear on the rotor or lobe surface simultaneously. As shown in FIGURE 1, the rotor is in such a rotational position that the upper roller 15 is touching the outer tip of one of the three lobes while the lower roller is contacting one of the valleys between the lobes. When the rotor is rotated 180 degrees, the lowermost roller touches the outermost tip of one lobe while the upper roller touches the most radially inward point between the lobes. As the rotor 7 rotates, the gate 11 moves in such a manner as to reciprocate in the radially opposite slots 10. The upper and lower ends of the gate are secured by two connecting bars 18 and made integral with each other as a single assembly. FIGURE 3 shows a side view and FIGURE 5 shows an end view of the gate assembly. The two bars 18 are secured at each end of the gate so that the shaft 1 is straddled. There are four sleeve rollers 19, supported on bearing shafts 20, which roll in grooves 21 and support each side of the reciprocating gate so that the gate can move in a linear direction only. Thus, when the rotor 7 rotates the gate moves from the lowermost position to the highest and back again causing reciprocation as the rotation of the rotor continues. The curve of the rotor is so generated that the reciprocation of the gate is a simple harmonic motion with gradual acceleration and deceleration, while the rotor rotates with uniform speed.

The spacing between the surface of the lobes of the rotor and the inner tips of the gate 11 is very close, with the cylindrical surfaces of the rollers 15 projecting about 2 to 3 thousands of an inch radially beyond the inner tips of the gate. This is in order to reduce sliding friction and to establish a rolling contact between the surfaces of the rotor 7 and of the gate 11 and to keep leakage to a minimum.

In FIGURE 5 is shown the narrow neck 22 which connects the upper and lower parts of the gate 11 to the bifurcated side connecting parts 23 forming a wide slot in between the two bars 18 to straddle the shaft 1. This arrangement forms a slot 24 between the outer connecting bars and the gate and makes possible the travel of the gate to the extreme upward or lowermost positions without interference with the housing ends 4 and disks 25. The housing and disks are provided in order to form a virtually airtight means to cover the slots between the connecting bars and the gate and to fill a portion of the slots 10. The disks 25 are assembled in the recess of the end housing 4. The inner surface of the rims 26 of the same recess comprises a circular projecting boss of the cylindrical housing 8 and thus securely holds the cylindrical housing from expanding as a result of the slots 10 which are in its perimeter. Machine screws 28 pass through the outer end housing 4, through the disk 25 and thread into the ends of the housing 8 to secure the assembly of the component parts together. The holes 29 on the disk 25 through which passes the shaft 1 are covered closely by the ends of the rotor 7 so that virtually no fluid can escape through the holes. The configuration of the neck 22 and its semicircular edge 31 and the semicircular formations 30 are such that the ends of the gate 11 always fill the spaces 10 regardless of the position of reciprocation of the gate and thus prevent air leakage. Air is trapped between the housing 8 and the lobes of the rotor 7 and cannot escape except through the inlet orifices 32 and the outlet orifices 33.

In operation, as the rotor 7 is made to rotate by application of an external power to the shaft 1, the air in space A which is trapped between the lobes 7c and 7b, the housing 8, and the disks 25, is further compressed as the volume in space A becomes smaller. Further rotation of the rotor 7 causes the rollers 15 to roll down the sloping side of the lobe 7b and the gate 11 which forms a part of the boundary of the space A which is holding a quantity of air in confinement. Simultaneously, air is entering spaces C and D through the air inlet ports 32. A series of exhaust orifices 33 are provided in the protruding portions 9 of the housing 8, and in these are placed spring loaded valves, consisting of a metallic lining 35 which is covered with a layer 36 of a suitable type of self lubricating and high heat resistant material, held by springs 34 against the seats 37 at the bottom of the exhaust orifices 33 and secured at the other ends of the orifices by the pads 38. In the center of the valve seats 37 there are annular openings 39 through which the compressed air may pass from space A, when the rotor 7 has rotated far enough from the initial position to increase the pressure in space A to a point slightly greater than that in the compressed air exhaust line 40. Then the spring 34 is compressed until the lower end of the valve covering 36 is sufficiently raised to allow the air to enter the opening 39 and pass through the opening 41 into the compressed air pipe line 40. When the lobe 7c has rotated until its tip is under the opening 39 all the air in space A is forced into the air line 40 through the opening 39. At this point, the pressure in the springs 34 and the back pressure in the compressed air line 40 force the valves 36 down on the seats 37 preventing escape of the air which has been compressed.

The right half of the pump is compressing air simultaneously as the left half. This means that the cubical volume of the three spaces between the three lobes of the rotor 7 and the annular outer housing 8 is emptied of the air twice for each revolution of the rotor. This makes for high volumetric efficiency. This efficiency can be augmented by utilizing the space in the slots 10 as a compression chamber, as shown in FIGURE 8. By providing an opening 42 at each end of the slot and insertion of suitable check valves into these openings, air or other fluid can be admitted into this chamber during the withdrawal of the gate 11 from the slot and compressed during the entrance of the gate into the slot and exhaust through the port 43 which can also be provided with a spring loaded check valve to permit exhaust at a suitable pressure. The arrows 42a show input and arrow 43a shows exhaust.

The chamber in the slot 10 may also be used to pump a second fluid or liquid, such as gas or fuel oil, while the rotor 7 is pumping another fluid or air. It may also serve to deliver a lubricant to prime the rotor.

By utilizing the chamber in the slot 10 as shown, the system can be used as a prime mover, by providing a fuel injector and a spark plug at 32, causing an explosion of

fuel and air. This causes the rotor 7 to rotate and actuate the ends of the gate as pistons in the slots 10, thereby acting as a converter of rotary motion into reciprocating motion. Conversely, causing a fuel-air infeed and explosion in slot 10 will, by reciprocating the gate 11, convert its reciprocating motion into rotary motion of the rotor 7.

The pump described herein can be used as an air metering pump by removal of the springs 34 and the valves 35. The chamber in slot 10 can be used simultaneously to meter fuel by provision of inlets 42 and outlets 43.

Other modifications and applications can be developed by those skilled in the art. It is not our intention to limit this invention to the examples shown but to define it by the appended claims.

We claim:

1. In a positive displacement pump, a circular cylindrical housing, a rectangular chamber extending radially outward of said housing and disposed diametrically opposite a second chamber extending radially outward of said housing, a pair of inlet ports disposed into said housing diametrically opposite with respect to each other, a pair of outlet ports leading from said housing and disposed diametrically opposite with respect to each other, end plates on the top and bottom of said housing, a multilobed rotor in said housing, a shaft supported centrally to and between said end plates and passing through the center of said rotor, a gate joined at its top and bottom by bifurcated bars straddling said shaft, an opening in said gate substantially equal in width to the diametric distance from the bottom of a valley between two adjacent lobes to the tip of the diametrically opposite lobe of said rotor and in height to the length of the face of said rotor, a pair of roller bearings mounted on each inner axial face of said opening and disposed opposite with respect to each other at the ends of the said face, each bearing extending axially a small portion of the respective end of said face, said bearings adapted to roll between the inner face of said opening and the surface of the lobes of said rotor and to prevent the inner face of said opening from contacting said rotor, said rotor constructed to reciprocate said gate diametrically in said chambers by the rotation of said rotor, the reciprocation of said gate and rotation of said rotor serving to draw a fluid into said housing through said inlet ports and to discharge the fluid through said outlet ports.

2. The pump described in claim 1, including, in addition, an inlet port in said chamber and an outlet port in said chamber, whereby a fluid is pumped through said chamber by the reciprocation of the gate in said chamber.
